RACKET FOR TENNIS AND LIKE GAMES

Emile Henri Aubert, Paris, France, assignor to
 Societe pour la Realisation et l'Exploitation
 d'Inventions Mecaniques "Reim", Neuilly-sur-
 Seine, France

Application January 22, 1937, Serial No. 121,899
 In France January 28, 1936

11 Claims. (Cl. 273—73)

This invention relates to rackets for tennis and like games.

The invention has for its object to provide a racket which has a simple construction, which is of a low cost price and in which the string network can be readily stretched and slackened at will.

The invention has further for its object to provide a racket in which the strings may have a higher tension than heretofore, owing to the fact that all the strings are stretched simultaneously thus avoiding all stresses of distortion upon the frame.

The invention has further for its object to provide a racket in which the strings can be mounted by any person, for the whole or in part, without special tools and without initial tension.

The invention will now be described with reference to the accompanying drawings, which are given merely by way of example, and in which:

Fig. 1 is a partial view, in section, parallel with the faces, of a racket according to the present invention, which is represented with its network slackened.

Fig. 2 is an analogous partial view, but with the network stretched.

Fig. 3 is a front view of one of the two flexible traction bands, of the embodiment shown in Fig. 1.

Fig. 4 is a side view corresponding to Fig. 1.

Fig. 5 is a cross-section of the frame, on the line 11—11 of Fig. 1, but on a larger scale.

Figs. 6 and 7 are respectively a side view and a front view corresponding to Fig. 1 of one of the small pulleys which are mounted on the bars of the flexible bands in order to facilitate the formation of loops in the string of which the network is formed.

Fig. 8 is a longitudinal section of one of the riders of Fig. 1, to which is attached one of the flexible traction bands, and of the nut which is screwed upon one of the threaded parts of the operating screw.

Fig. 9 is a side view of the rider shown in Fig. 8 which serves for the attaching.

Fig. 10 is a plan view of the same.

Fig. 11 is a longitudinal section, on the line 11—11 of Fig. 12, of a modified form of the flexible traction band.

Fig. 12 is a corresponding plan view.

In the embodiment represented the invention is supposed to be applied to a racket having a wood frame and handle. The frame 1 extends at 1^a as far as the end of the handle. An axial portion 20^a forming the throat-piece, also extends

to the rear end of the handle. The combination of the extensions 1^a and of the throat-piece 20^a is joined together by cementing and/or by screws 12. At the outer part, and on either side of the middle part 20^a and of the extensions 1^a, are preferably cemented, in the known manner, suitable strengthening plates and curved pieces 62 (Fig. 4), consisting of wood, the fibres of these pieces being perpendicular or oblique to the fibres of the pieces which they cover. Furthermore, a curved piece 64 is cemented, for strengthening purposes, in the interior of the frame and adjacent the throat-piece.

On either side of the throat-piece and as far as the transverse axis of the frame, the said frame 1 comprises on its outer face a groove 65 (Fig. 5) having a small depth but a relatively considerable width. In each of the grooves 65 is engaged a rib 72 (Fig. 5) formed on a member 73 (Figs. 1, 2 and 5) secured by cementing or otherwise to the lateral face of the frame 1. The said rib does not entirely fill the said groove in the frame 1, thus leaving a space having a flat section. The said groove is sectioned axially upon its whole length by a narrower groove 74 (Figs. 1, 2 and 5), which latter is formed in the member 73 and extends towards the interior of the frame 1 beyond the groove 65. The groove 65 and the portion of the groove 74 provided in the frame 1, form together a substantially T-shaped groove in the frame. The said frame is pierced upon its whole periphery, with the exception of the throat-piece, with holes 67 which are situated adjacent the two grooves 65, and open into these latter.

In each groove 65 is freely slidable a traction band 75, which is adapted to support a considerable tractive force (such as 1000 to 1500 kgs.). The bands 75 may consist of a steel of great strength, and they are sufficiently flexible to fit upon the curved part of the frame without difficulty.

Each band 75, whose thickness may be constant, may have a constant width, or preferably, its width may diminish from the end next the throat-piece, to the other end, as shown in Fig. 3. In fact, the stress upon the metal decreases from the end 76 to the end 77, and the form represented in Fig. 15 permits of reducing the weight without prejudice to the strength.

The bands 75 comprise, upon their whole length, perforations 78, leaving between them transverse bars 79. Upon each bar is engaged, owing to a radial notch 80 (Figs. 6, 7, 8) a small grooved pulley 81.

Adjacent the throat-piece 20^a, the bands 75 are attached by their last perforations 78 to the upper lugs 82 (Figs. 1, 2, 8, 9, 10) of two riders 83, which may consist of suitably bent sheet metal and have a general section in the form of an inverted T (Fig. 9). They are slideable in a transverse aperture 84 of corresponding form (Figs. 1, 2, 4) which is pierced clear through the throat-piece 20^a and the extensions 1^a of the frame. Preferably, the sliding of the two riders 83 in the aperture 84 is facilitated by very hard metal friction plates 85—86 which are mounted in said aperture and make contact respectively with one of the shoes 87 of each rider and with the bands 75.

Each rider 83 forms a sort of forked bracket which is rotatable on a cylindrical member 89 whose axis is perpendicular to the faces of the racket. The two members 89 serve as nuts, and for this purpose they are tapped according to an axis parallel with the axis of the aperture 84 and perpendicular to the axes of the cylindrical surfaces of the said members 89. The nuts 89 are screwed to respective parts 90—91 of an operating screw, threaded in contrary directions, which is situated in the aperture 84. The said screw (90—91) has at one end a square part 92; male or female, by which it can be turned by a key. A central shoulder 93 separates the two inversely threaded parts 90—91.

The network, which is mounted and stretched upon the said frame, consists of a single flexible string (catgut, cord or wire) which is mounted in zigzag in two directions X—X, Y—Y which are inclined and in symmetrical position with reference to the longitudinal axis of the racket, the two ends of the string being joined together by a knot. At one end of each zigzag, the two strands of the flexible string 13 form a loop passing through two successive holes 67 in the frame 1; at the other end of each zigzag, the two strands forming the next loop, pass through two successive holes 67 in the frame 1, and also through two successive perforations 78 in one of the two flexible bands 75, the loop being placed around the pulley 81 which is mounted on the transverse bar 79 of the band, located between the two aforesaid perforations 78.

The stretching is obtained by turning the screw (90—91) in the direction which will bring the two nuts towards the longitudinal axis of the racket, and the said nuts will assume, for instance, the position represented in Fig. 2, drawing with them the riders 83, and these latter will draw upon the flexible bands 75 in the direction of the arrows f² and f³ (Fig. 1). The pulleys 81 will thus move with reference to the perforations 67 of the frame 1, thus lengthening the loops which are formed around them. This lengthening causes the general and simultaneous stretching of the network 13.

In order to slacken this network, it is simply necessary to turn the screw (90—91) in the contrary direction, so as to separate the nuts 89 and hence the riders 83; Fig. 1 shows their position when the network is slackened. It should be noted that since the said riders are pivotally mounted on the cylindrical nuts 89, these nuts are not subjected to any lateral stress, in spite of the fact that the reactions of the bands 75 are eccentric with reference to the axis of the screw 90—91. These reactions are in contrary directions, and are balanced by the use of the riders 83, the nuts 89 and the screw 90, 91, independently of the throat-piece 20^a, and for this reason, the

latter is not subjected to any stresses due to the fact that the network 13 is stretched and is maintained in this position.

Figs. 11 and 12 show a modified form of the band 75, in which the separately-mounted pulleys 5 used in the preceding construction are replaced by simple lugs which are suitably bent at 95, such lugs resulting from the formation of the perforations 78 by a partial punching of the band.

Obviously, the invention is not limited to the 10 embodiments herein described and represented, which are given solely by way of example. In the devices represented, the perforations 78 of the bands 75 and the perforations 67 of the frame 1 are supposed to be equidistant, but in order to 15 obtain elongations of the strands of the network 13 which are practically proportional to the lengths of the different strands, the perforations 78 of the bands 75 and/or the perforations 67 of the frame 1 may be unequally spaced. 20

The pieces 73 which are mounted laterally on the frame 1 in order to conceal the bands 75, are of optional use; they may be eliminated, and in this case the bands 75 are quite visible, and are flush with the lateral face of the frame. 25

Obviously, the said invention is as well adapted to rackets with metallic frames as to rackets with wood frames, and the frame may have any form, whether oval, round or the like.

Having now described my invention, what I 30 claim as new and desire to secure by Letters Patent is:

1. A racket for tennis or like games, comprising in combination an open frame with handle, a string network stretched across said frame, 35 on either side of the longitudinal axis of said frame a flexible metallic band bearing flatwise on said frame and adapted to support said network and to slide along said frame and means adapted to exert a traction upon said bands to 40 slide them along said frame, whereby said network can be stretched or slackened at will.

2. A racket for tennis or like games comprising in combination an open frame with handle and provided with holes, a string network 45 stretched across said frame with its different strands passed through said holes, on either side of the longitudinal axis of said frame a flexible metallic band bearing flatwise on said frame and adapted to slide along said frame and provided with perforations leaving between them strips of the metal of the band about which strips are looped, the strings of said string network and means adapted to exert a traction upon said bands to slide them along said frame. 50

3. A racket as claimed in claim 1, in which said bands are connected together and are free to slide as a whole along the frame in either direction. 55

4. A racket for tennis or like games comprising in combination an open frame with handle, a string network stretched across said frame, on either side of the longitudinal axis of said frame a flexible metallic band bearing flatwise on said frame and adapted to support said network and to slide along said frame, a screw having two parts threaded in contrary directions and arranged in a transverse aperture provided in the throat-piece of the racket in which it is capable of sliding longitudinally, two nuts, one screwed on each of said two parts and adapted to slide without rotating in said aperture, connecting means adapted to connect the ends adjacent said throat-piece of said two bands with said nuts, whereby, when said screw is rotated, said two nuts are 60 65 70 75 80 85 90 95 98 99 100

displaced along said screw in contrary directions and are adapted to exert an equal traction on each of said bands.

5. A racket as claimed in claim 4, in which said connecting means are constituted by riders adapted to engage walls of said transverse aperture and in which said nuts each comprise axles which are perpendicular to the axis of said screw and are at right angles to the plane of said frame, 10 said riders being adapted to pivot about said axles.

6. A racket as claimed in claim 4, in which said nuts have externally the form of a cylinder the axis of which is perpendicular to the axis of 15 said screw and at right angles to the plane of said frame, in which said connecting means are constituted by riders adapted to pivot about said cylinders and adapted to engage walls of said transverse aperture and further comprising protecting metal plates lining the walls of said aperture which are engaged by said riders and said bands.

20 7. A racket as claimed in claim 2, in which the metal corresponding to the perforations is bent on each side of said strips so as to form 25 a round guiding surface.

8. A racket as claimed in claim 2, in which said

strips are unequally spaced so as to determine for each of them, with reference to said holes, a starting position which is such that for a given displacement of said bands, the same tension will be set up in the different strands of the network, irrespectively of their differences in length.

5 9. A racket as claimed in claim 4, in which said connecting means are constituted by riders adapted to engage walls of said transverse aperture and in which said nuts each comprise axles 10 which are perpendicular to the axis of said screw and are at right angles to the plane of said frame, said riders being adapted to pivot about said axles, and being each formed with a lug adapted to penetrate a perforation of said bands.

15 10. A racket as claimed in claim 1, in which said frame comprises on its outer face a longitudinal substantially T shaped groove providing for two shoulders on which bear said bands.

20 11. A racket as claimed in claim 1, in which said frame comprises on its outer face a longitudinal substantially T shaped groove providing for two shoulders on which bear said bands and a covering member formed with a rib partially engaging the widest part of said groove and having 25 a longitudinal slit.

EMILE HENRI AUBERT.
